APPARATUS FOR FLOWING VISCOUS LIQUIDS, INCLUDING A BY-PASS BETWEEN A PUMP OUTLET AND THE LIQUID CHAMBER

George S. Pyles, Glendale, Calif.

Application September 17, 1945, Serial No. 616,754

3 Claims. (Cl. 222—318)

1

My invention has to do with an apparatus for flowing viscous or colloidal liquids, such as plastic solutions, onto the surfaces where they are to be used.

Heretofore, in the use of such liquids it has been deemed necessary to brush the solutions onto the surface of use because of the impracticability of those efforts which have heretofore been made to force them by pressure through a hose and nozzle. Such attempts have proven impracticable largely because, if such materials are subjected to any considerable air pressure, they tend to "roll" in emerging from the hose, due perhaps to air pockets causing back pressures, with the result that no uniformity of flow can be obtained, and, due to the characteristics of such materials, if low pressure is used, no adequate flow is obtained. Moreover, in handling such materials it is highly important to keep them free of exposure to air as far as possible since air exposure causes chemical reactions tending to clog the apparatus.

In other words, it has been found impossible with known apparatus to obtain desirable and practicable flowing conditions for such materials.

I have found that I am able to completely overcome the difficulties which have been experienced in this art by using as the storage for the solution a pressure pot in which pressure is exerted on the solution by a fluid-actuated piston. I use the pressure pot merely for forcing the solution into the intake of a pump which finally forces the solution through a delivery hose. I remove all excessive pressure by providing a constantly open adjustable return conduit from the pump to the pressure pot, which enables the pump to be operated even though the delivery valve of the hose is closed, without exerting excessive pressure on the material in the hose.

It is therefore among the objects of my invention to provide an apparatus for flowing viscous solutions without subjecting them to excessive pressures.

It is also an object to provide an apparatus wherein the solution is not exposed to air prior to emerging from the delivery hose.

More specifically it is an object to provide apparatus for such purpose utilizing, in combination, a pump, a pressure pot for delivery of the solution to the pump and means for returning excess material from the pump to the pressure pot.

My invention also contemplates a novel pressure pot construction for use in such assembly.

Other objects and advantages of my inven-

2

tion will appear from the following detailed description of a particular embodiment in which the single figure illustrates somewhat schematically an apparatus unit for carrying out the invention, the pressure pot or reservoir element being shown in medial section.

Referring now to the drawings I show at 5 a platform mounted on casters 6 for portability. On the platform I support, as by legs 8, a pressure pot or reservoir generally denoted 10 and comprising a cylinder 11 having a bottom end closure 15 and a top closure 16 retained in position by screw clamps 17. A piston 20 is slidably mounted in the cylinder and divides the cylinder into a solution chamber 25 and a pressure chamber 26, the solution chamber being variable in capacity in response to movement of the piston.

A conventional gear pump is shown in side elevation at 30 supported on the platform as by base 31, and a conventional air motor 35 is supported on the platform as by base 36, the motor being operatively connected to the pump by a drive shaft 38. Air under pressure communicates with the pressure chamber through a conduit 40 and a T connection 41, from an air pressure source not shown, a pressure gauge 43 being connected into the T. Gate valve means 45 controls admission of air into the apparatus from the source and, from one leg of the T and through a control valve 47, a flexible conduit 48 leads to the air motor to operate the latter in order to drive the pump.

From an outlet port 50 in the bottom of the pressure pot a conduit 51 leads to the inlet of the pump. The outlet of the pump is provided with a T fitting 52, one leg 55 of which carries a pressure gauge 56 and a control valve 57, the latter leg having connected to it a final delivery hose 58 carrying at its end a suitable nozzle 59. From leg 60 of the T 52 and through a control valve 62, a return conduit 63 leads into the solution chamber 25 through fitting 65 mounted in the top wall of the pressure pot, and thence through a flexible hose 66 and port 67 through piston 20.

In operation, air enters chamber 26 through T fitting 41 and at the same time enters the air motor through conduit 48, thus simultaneously forcing the piston downwardly in the cylinder 50 to force solution from chamber 25 into the pump inlet and starting the pump by means of the air motor. The valve 62 may be set so that any desired pump pressure is delivered on the solution in hose 58 and this pressure will be at all times 55 maintained uniform since any excess pressure is

relieved by return of solution from the pump to the solution chamber. When the valve 57 is closed, as frequently takes place in use, as for instance when the user moves the nozzle from one spot to another, all the solution taken into the pump will be returned to the chamber 25, thus relieving the liquid in line 58 of any pressure.

I claim:

1. Apparatus for effecting pressure flow of viscous liquids comprising, in combination with a driven pump having a liquid inlet and a liquid outlet, a tank, a piston reciprocably mounted in the tank for movement to impose pressure upon liquid in a liquid chamber portion of the tank, means providing communication from the liquid chamber to the pump inlet, means acting upon the piston to move the same to impose pressure upon the liquid to force liquid from the liquid chamber through the pump inlet, and means establishing communication between the pump outlet and the liquid chamber through the piston.

2. Apparatus for effecting pressure flow of viscous liquids comprising, in combination with a driven pump having a liquid inlet and a liquid outlet, a tank, a piston reciprocably mounted in the tank and dividing the tank into a liquid chamber and a pressure chamber, means providing communication from the liquid chamber to the pump inlet, means for introducing fluid under pressure into the pressure chamber whereby to cause the piston to force liquid from the liquid chamber into the pump inlet, and means

establishing communication between the pump inlet and the liquid chamber through the pressure chamber and piston including a flexible conduit extending through the pressure chamber.

5 3. Apparatus for effecting pressure flow of viscous liquids comprising, in combination with a source of fluid pressure, a tank, a piston reciprocably mounted in the tank and dividing it into a pressure chamber and a liquid chamber 10 of variable capacity, means establishing communication between the source of fluid pressure and the pressure chamber to actuate the piston, a pump having its intake in communication with the liquid chamber, a flow line in communication with the pump outlet, means establishing return flow communication from the pump outlet to the liquid chamber through the pressure chamber and through the piston, and means responsive to fluid pressure from the source to drive the pump.
